METHOD AND MEANS FOR STOPPING A WEAVING MACHINE

Erwin Pfarrwaller, Winterthur, Switzerland, assignor to Sulzer Frères, Société Anonyme, Winterthur, Switzerland, a corporation of Switzerland

Filed Sept. 14, 1955, Ser. No. 534,342

Claims priority, application Switzerland Oct. 2, 1954

1 Claim. (Cl. 139—353)

The present invention relates to a method and means for stopping a weaving machine for correcting irregularities of the warp.

The method according to the invention includes the step of producing a control pulse for stopping the weaving machine in dependence on an irregularity of the warp and on a predetermined angle of rotation of the main shaft of the weaving machine, at which angle of rotation the movement of the warp threads changing the shed is stopped between the two extreme open shed positions. Warp threads which do not change shed are moved from an extreme upper or lower position toward closed shed position and back therefrom to the extreme position while the warp threads which do change shed are moved all the way from extreme upper to extreme lower position, or vice versa. In the method according to the invention, the movement of the warp threads which do not change shed is stopped somewhere between one of their extreme positions and the positions where they are normally reversed or is stopped at the point of reversal. Depending on the speed of the loom and the masses which must be stopped, the stop motion is actuated prior to the moment when actual stoppage of the loom is desired.

The means for performing the aforesaid method include a control device which effects stopping of the weaving machine in dependence on an irregularity of the warp as well as on a predetermined rotational angular position of the main shaft of the weaving machine. The means for performing the method also include a device which actuates the heddles controlling the warp in such a manner that at the predetermined angular position of the main shaft the movement of the warp threads changing the shed is stopped between the two extreme open shed positions. The invention also refers to a loom for weaving having a shedding mechanism producing a binding other than 1:1 in which some warp threads need not change shed while other warp threads do change shed. The warp threads which do not change shed are moved from the extreme upper or lower position toward closed shed position and back while the warp threads which do change shed move all the way from one extreme position to the other extreme position.

The novel features which are considered characteristic of the invention are set forth with particularity in the appended claims. The invention itself however and additional objects and advantages thereof will best be understood from the following description of embodiments thereof when read in conjunction with the accompanying drawing, in which

Fig. 1 illustrates a weaving machine seen from the fabric beam side;

Fig. 2 is a part sectional view of a mechanism for actuating the heddles of the weaving machine;

Fig. 3 is a part sectional view of the mechanism shown in Fig. 2, the section being taken along line III—III of Fig. 2;

2

Fig. 4 is a diagrammatic illustration of the stopping device according to the invention;

Figs. 5 and 9 are diagrams showing the movements of the lay and of the heddles;

Figs. 6, 7, 8, and 10 illustrate different positions of the warp threads when the weaving machine is stopped;

Figs. 11 and 12 are large scale illustrations of the cams actuating the heddle frames in the mechanism shown in Figs. 2 and 3;

Fig. 13 is a diagrammatic illustration of a modified stopping device according to the invention.

The same numerals designate the same parts in all figures.

Referring more particularly to Fig. 1 of the drawing, 15 the drive of the loom includes a motor 11 which is mounted on a right side shield 12 and which drives a belt pulley 14 by means of a belt 13. A disc clutch mounted in the pulley 14 and not shown drives the main shaft 15 of the loom. The shaft 15 primarily drives the 20 parts of the loom which must be moved continuously or intermittently during normal operation of the loom. The shaft 15 actuates the warp beam 16 and the warp 17 which moves through the heddles supported by one or a plurality of frames 18, the latter being actuated by the shaft 15 for opening, closing, and changing of the 25 shed. The shaft 15 also actuates the warp actuating beam 19 and the cloth beam 20 for winding the cloth 21.

A picking mechanism 22 and a shuttle receiving mechanism 23 are also driven by the shaft 15 by means 30 of intermediate drives. A weft thread 24 is transferred to a shuttle 25 in the picking mechanism 22. The weft thread is pulled from a spool 27 supported by a carrier 26 outside of the shuttle 25 and is picked by the 35 shuttle 25 through the shed towards the receiving mechanism 23, whereupon the weft thread 24 is beaten up by means of a lay actuated by the shaft 15.

The shuttle 25, after the weft thread 24 has been disengaged therefrom, is moved onto a return mechanism 30 by suitable means in the shuttle receiving mechanism

40 23. The return mechanism, driven by the main shaft 15, returns the idle shuttle 25 below the shed from the receiving mechanism to the picking mechanism.

A drive 32 for the actuating beam 19 is mounted on a left side shield 12a which is connected with the right side shield 12 by means of a box girder 31 to form a 45 rigid frame for the weaving machine.

Control levers 33 and control shaft 34 afford actuation of the above mentioned clutch by means of a linkage 35 and of a brake disk by means of a linkage 36 50 for effecting starting and stopping of the loom from various localities around the loom. The brake, which is in a housing 37 and acts on the main shaft 15, is applied at improper operating conditions after disengagement of the clutch in the belt pulley 14 for immediately 55 stopping the main shaft 15 and all parts driven thereby.

The brake in the housing 37 is disengaged in known manner by means of the control levers 33 without engaging the clutch in the pulley 14. Thereupon the disconnected main shaft 15 can be turned by means of a hand wheel 38, for example for adjusting individual loom 60 parts, to assume a desired position relative to zero position of the main shaft. The latter is thereby revolved until it assumes the angular position corresponding to the loom part which is being checked.

65 Figs. 2 and 3 illustrate a device for actuating heddles 18a to 18d. There are two shafts 41 and 42 which are driven by the main shaft 15 through a reducing gear train 43. The rotational speed of the shafts 41 and 42 is one-fourth of that of the main shaft 15. Sets of cams 45a to 45d and 46a to 46d are made fast on the shafts 41 and 42, respectively. The cams actuate cam follower 47a to 47d, the latter actuating the heddle frames

18a to 18d through elbow levers 48a to 48d, respectively. A dial 50, showing angles 0° to 360° on a scale 51, is mounted on the main shaft. A pointer 52 mounted on a casing 40 indicates the angular position of the shaft 15 on the scale 51. The position of the heddles shown in Fig. 2 corresponds to an angular position of 30° of the shaft 15. Fig. 3 shows the extreme upper position 53 and the extreme lower position 54 of the upper beams of the heddle frames.

Fig. 4 illustrates a device for stopping the weaving machine, numeral 55 designating a brake disc on the main shaft 15 and located in the housing 37 (Fig. 1). A lever 57 swingable on a pivot 58 and having a free end which is connected with a spring 59 serves to operate a brake band 56. The free end of the lever 57 is also connected by means of a link 61 with a lever 62 revolving about stationary fulcrum pin 63 and having a recess 64 receiving a locking lever 65 mounted to a stopping shaft 66 which is supported by the frame of the weaving machine.

The stopping device includes control means having a contact disc 67 supported by the main shaft 15; a contact element 68 cooperating with slide contacts 69 is movably mounted on the disc 67 and can be fixed in a selected position. The disc 67 is revolvable on a hub 70 which is fast on the shaft 15, the disc being pressed to a flange 72 of the hub 70 by means of a screw 71. The flange 72 is provided with a scale 73. The disc 67 is provided with a marker 74 for indicating the relative angular position of the disc 67 and the flange 72. The contact element 68 can be fixed in any desired position by tightening a screw 88 which extends into a nut placed on the back of the disc 67, the pointer 89 at one end of the element 68 showing the adjustment angle relative to the marker 74 on a scale 90.

The warp 17 moves over rods 75 supported by the frame of the weaving machine and the individual warp threads move through individual feelers 76 arranged in a file one behind the other on a contact rail 77. A solenoid 80 is interposed in the electric circuit 78 which is supplied by a battery 79 and includes the rail 77 and the slide contacts 69. An armature 81 is held in the upper position shown in Fig. 4 by means of a spring 82. The armature 81 is provided with a hook 83 which cooperates with an arm 84 of the locking lever 65 on the stopping shaft 66. The arm 84 is pressed upwards by a spring 85.

If there is an irregularity in the warp, for example a broken warp thread, a pulse is produced by the irregularity as well as at a predetermined angular position of the main shaft 15 which pulse energizes the solenoid 80. If a warp thread breaks, the respective thread feeler 76 drops onto the rail 77, grounding the circuit 78. The circuit 78, however, is not closed until also the slide contacts 69 are connected.

If the circuit 78 is closed, the armature 81 is pulled down against the action of the spring 82 and the hook 83 rotates the lever 84, 65 counterclockwise, moving the locking lever 65 out of the recess 64 and releasing the lever 62. The loom stopping shaft 66 is rocked in a loom stopping direction. The lever 62 is rotated counterclockwise by the action of the spring 59. The latter also moves the brake lever 57 clockwise, tightening the brake band 56 on the brake disc 55. This initiates braking of the main shaft 15, stopping the main shaft 15 after rotation through a certain braking angle.

There are, of course, conventional means (not shown) for interrupting current supply to the motor 11 and/or for disengaging the clutch in the pulley 14.

The line A in the diagram Fig. 5 indicates the movement of the lay. From point f the lay moves toward the fabric, beating up the inserted weft thread at point g and returning at point h to its idle position. The curve B indicates the movement of the heddle frame 18a, the curve C indicates the movement of the heddle frame 18b, and the curve D indicates the movement of the heddle frames 18c and 18d which are shown in Fig. 3. The

movement of the frames 18a and 18b commences at the points i, whereas the frames 18c and 18d begin their movement at point k. The last-mentioned heddle frames remain in the upper shed position in which they already were and assume only temporarily a position below the extreme upper shed position.

The angular position VI of the main shaft 15 in the diagram Fig. 5 corresponds to the position of the heddles 18a to 18d in Fig. 6 which are still in their extreme upper shed positions (18b, 18c, 18d) and in the extreme lower position (18a). The warp 17 and the fabric 21 extend between the warp beam 16 and the cloth beam 20. The lay 28 with the reed 29 is still in rest position.

For correcting an irregularity in the warp, the weaving machine must be stopped while the angular position of the main shaft is between m and n, i.e. in the range which is shaded in Fig. 5. The position of the heddle frames in the angular position VII (Fig. 5) of the main shaft corresponds to the situation shown in Fig. 7. The warp threads extending through the heddles 18a and 18b have already been crossed at position o in Fig. 5, the heddles being within the range defined by their extreme positions 53 and 54 at the moment they are stopped, so that drawing in of new warp threads to replace the broken threads is facilitated. The eyes of the heddles are considerably better accessible for threading when the heddles are in an intermediate position than when they are in their extreme upper or lower position. Accessibility of the eyes of the heddles which are in uppermost position is frequently impaired by the upper beams of the heddle frames which are in their lower shed position.

The angular range between the positions m and n of the main shaft is ahead of the angular position g of the main shaft 15 in which position the reed 29 is beating up a weft thread, the distance p between the angular positions n and g being preferably made so great that there is sufficient time to accelerate the weaving machine to full speed between the moment when the machine is restarted and the moment at which a weft thread is beaten up, so that the weft thread is beaten up in a manner excluding an irregularity in the fabric 21.

After the beat-up position g another range shown shaded in Fig. 5 is provided between the angular positions q and r within which range the weaving machine may be stopped for correcting an irregularity in the warp. The angular position VIII corresponds to the situation shown in Fig. 8 where the heddles are in substantially the same position as in Fig. 7. The lay 28 and the reed 29, however, are moving to the left toward rest or inactive position. The first angular position q of this range is at a distance s from the beat-up position g, so that, when the weaving machine is restarted, the beginning of the movement of the lay cannot cause irregularities in the fabric. To accomplish this, it is sufficient that the reed 29 is just a little removed from the last inserted weft thread. The distance s can therefore be considerably smaller than the distance p.

The angular positions VII, and VIII in which the weaving machine is standing still are not the positions in which an impulse for stopping the machine is produced. The dependency of the production of the impulse for stopping the machine on the irregularity in the warp is effected by the contact made between the respective warp thread feeler and the rail 77.

The dependency of the stopping of the weaving machine on a predetermined angular position of the main shaft 15 is effected as follows: The mark 74 on the contact disc 67 is placed at the desired angle on the scale 73 (Fig. 4). The setting shown in the drawing corresponds to an angular position of the shaft 15 amounting to 30° past the zero position of the shaft 15. In order to be sure that the machine is actually at a standstill at this angular position of its main shaft, the impulse must be produced so many angular degrees ahead

of the desired angular degree as correspond to the braking angle.

In machines operating at a very slow speed a braking angle of 0° may suffice, i.e. the contact element 68 can be so set that the pointer 89 coincides with the mark 74 or that the pointer 89 is at the zero line of the scale 90. In modern high speed weaving machines the braking angle, i.e. the angle through which the main shaft rotates between the moment when the pulse is produced and the moment when the machine comes to a standstill is between 20° and 30° . Therefore, the pointer 89 must be moved through this angle in the direction of rotation of the disc 67 (arrow 86), as is shown in Fig. 4.

The impulse for the angular position q to r must be produced before a weft thread is beaten up at position g . This has the advantage that the braking angle is reduced because the energy required for beating up the inserted weft thread retards the shaft 15 in addition to the effect of the brake 55, 56, so that the machine will be stopped sooner.

In contradistinction to the operation shown in Fig. 5, the heddles are simultaneously moved in the operation illustrated in the motion diagram Fig. 9. The heddle frames 18a and 18d which retain the existing shed position for the subsequent pick, move from the extreme positions 54, 53 into a half shed position as indicated by the lines B and E in which the warp actuated by the heddles 18a and 18d is approximately in the middle between lower shed position, respectively between upper shed position and middle shed position. The heddles 18b and 18c change the shed according to the curves C and D.

Fig. 10 shows the position of the heddles when the machine stands still at the angular position X (Fig. 9) of the main shaft in which position the warp threads changing the shed cross each other. The mechanism may be adjusted for other angular positions which are between the lines m and n in Fig. 9, the end of the range between these lines, i.e. the line n , being at a distance p from the beat-up position g for the reasons explained supra.

The radii I to IV marked on the cams 45a and 46a in Figs. 11 and 12, respectively, indicate the points of the cams in which the cam follower rollers of the levers 47 (Fig. 2) contact the cams in the intermediate positions Z_1 and Z_2 in which the weaving machine is brought to a standstill in dependence on the angular position VI in Fig. 5. The radii I to IV assume different positions depending on the choice of the angular position for stopping the machine within the ranges shown by the shaded areas in Figs. 5 and 9. The cams 45a and 46a shown in Figs. 11 and 12 are designed for a binding 1:3, the cams making a quarter turn at each pick. At the transition from lower shed to upper shed in the intermediate position according to the radius II, the heddles are in a lower intermediate position than at the positions according to the radii I, III, and IV, the radii III and IV corresponding to the half shed positions of the heddles remaining in their sheds. At the angular position, in which the movement of shed changing warp threads is stopped in a position situated between the two extreme positions at open shed, either all thread changing warp threads may be in this intermediate position or a part of the warp threads may, for any reason, remain in their extreme position.

Fig. 13 illustrates a modified mechanism which causes stopping of the weaving machine in dependence on a predetermined angular position of the main shaft. A cam 91 is adjustably mounted on the main shaft 15 or on another shaft rotating synchronously therewith, i.e. on a shaft which is driven at a speed corresponding to the number of picks per time unit or to an even multiple number or an even division thereof, so that the cam contacts a cam follower roller always at the same angular position of the main shaft 15. The cam 91 cooperates with a lever 92 which swings on a stationary pin 93. The

upper end of the lever 92 is pulled to the left by a spring 94 for pressing the cam follower roller 95 rotatably mounted on the lever 92 against the cam 91. An adjustable abutment screw 96 is screwed into the free end 5 of the lever 92 which screw can be secured in the desired position by manipulation of a lock nut 97.

A warp thread feeler 76 is provided for each warp thread 17 which is guided by rods 75, the thread feelers being arranged in a series one behind the other on a contact rail 77. An electric circuit 78' connects a battery 79 with a solenoid 80' whose armature 81' is pressed upwards by means of a spring 82. A latch 99 pivoted to a bolt 101 is connected with the armature 81' by means of a link 98. The right end of the bolt or tappet 101 carries a head 102 abutting against a lever or arm 103 which is fast on a stopping shaft 66' and which is pressed to the left by a spring 104 so that a collar 102' of the head 102 abuts against the side shield 12 of the frame of the weaving machine.

20 In the position shown in Fig. 13 the solenoid 80' is not energized and the pawl 99 is lifted due to the action of the spring 82 so that the latch is out of the way of the abutment 96.

At an irregularity of the warp, for example if a warp thread is broken, the respective warp thread feeler 76 drops onto the contact rail 77 so that the circuit 78' is closed and the solenoid 80' is energized and the armature 81' is pulled down. Thereby the latch 99 is pulled down to the position indicated by dash-dot lines in Fig. 13. As long as the roller 95 follows the circular portion of the surface of the cam 91, the abutment 96 is in the position shown in solid lines and does not touch the latch 99. However, when the cam portion 108 runs onto the roller 95, lever 92 is pressed into the position shown in dash-dot lines and the abutment 96 moves the latch 99 and the bolt 101 to the right so that the lever 103 is turned counterclockwise against the action of the spring 104. The shaft 66' carries a pawl 65' corresponding to the right arm of the lever 65, 84 40 of the device shown in Fig. 4, the pawl being taken out of the recess 64 of the lever 62 affording engagement of the brake 55, 56. The last described mechanism is the same as the one shown in Fig. 4 and its showing has not been repeated in Fig. 13.

45 The cam 91 is revolvable on a bushing which is fast on the shaft 15 and which has a flange 106. The relative position of the cam 91 and of the flange 106 can be fixed by tightening a screw 105 screwed into the cam 91 and having a head engaging the flange 106. The latter is provided with a scale 107 indicating the angular positions 0° to 360° of the shaft 15.

50 A mark 109 is provided on the cam 91 opposite the scale 107. This mark indicates an angle β of 45° . The angle β is composed of an angle of 60° , which is the angular position of the shaft 15 at which the weaving machine is to be stopped, minus a brake angle of 15° . The shaft 66' is revolved at an angular position of 45° of the main shaft 15 for initiating the braking operation. The shaft 15 does not come to a standstill until it has revolved through another 15° .

60 Instead of providing an adjustable abutment 96 on the cam follower lever 92, the latch or pawl 99 may be made longitudinally displaceable, for example by making variable the length of the bolt 101. As another 65 modification, an adjustment screw may be provided at the left end of the latch 99 instead of providing the adjustable abutment 96 on the lever 92. The latch 99 may be pivoted to the lever 103, omitting the bolt 101.

What is claimed is:

70 In a weaving machine for producing a fabric whose pattern is different from the pattern characterized by 1:1 whereby certain warp threads change shed while other warp threads do not change shed: a main drive shaft, a shedding mechanism operatively connected to said main drive shaft and including control means effecting

movement of the warp threads which do not change shed to a position between their extreme end positions at open shed and closed shed position and back to the previous extreme position during periods of time when the warp threads which do change shed move from one to the other of their extreme end positions at open shed, a lay operatively connected to said main drive shaft and being between a retracted position and beat-up position during said periods of time, and an apparatus for stopping the weaving machine including first means responsive to and actuated by an irregularity in the warp, second means responsive to and actuated at a predetermined angular position of said main drive shaft during said periods of time, and means for stopping the weaving machine upon coaction of said first and said second means, said second means including a cam rotating synchronously with the main shaft of the weaving machine, said stopping means including a lever provided with a cam follower roller engaged by said cam, a stopping shaft, an arm on said stopping shaft, a displacement

ble tappet abutting against said arm, a pawl pivoted to said tappet, and pawl actuating means for moving said pawl into a position in which it can be abutted by said lever, said pawl actuating means being operatively connected to said first means for moving said pawl into the position in which it can be abutted by said lever for displacing said tappet by said lever when the main shaft of the weaving machine is in the predetermined angular position and after occurrence of an irregularity in the warp.
